UNITED STATES PATENT OFFICE.

WILLIAM N. HORNE, OF NASHVILLE, TENNESSEE.

DESIGN FOR A SHOE.

SPECIFICATION forming part of Design No. 33,765, dated December 18, 1900.

Application filed November 13, 1900. Serial No. 36,412. Term of patent 14 years.

To all whom it may concern:

Be it known that I, WILLIAM N. HORNE, a citizen of the United States, residing at Nashville, county of Davidson, and State of Tennessee, have invented and produced a new and original Design for a Shoe, of which the following is a specification, reference being had to the accompanying drawings, forming part thereof.

10 Figure 1 is a perspective of a shoe, showing my new design; and Fig. 2 is a plan thereof.

As shown in the drawings, the leading or material feature of my design consists of the shape of the gores A A' in the sides of the 15 upper, the forward gores A extending from the top of the shoe downwardly and forwardly on reversely-curved lines along the instep at each side of the front section B, thus leaving the solid side portions D, while the rear curved

gores A' extend down from the top of the 20 shoe to the upper edge of the vamp, thus leaving the narrow backstay C between them. The edges of every gore extend in approximately parallel lines from the top of the shoe, so that the gores A A' present a reversely- 25 curved appearance, as above stated.

Having thus described my invention, what I claim as new, and desire to secure by Letters Patent, is—

The design for a shoe, as herein shown and 30 described.

In testimony whereof I affix my signature in presence of two witnesses.

WILLIAM N. HORNE.

Witnesses:

J. E. WADDEY,

J. M. EATHERLEY.
